UNITED STATES PATENT OFFICE.

DANIEL H. MURPHY, OF PITTSBURGH, PENNSYLVANIA, ASSIGNOR TO AMERICAN CONDUIT MANUFACTURING COMPANY, OF PITTSBURGH, PENNSYLVANIA, A CORPORATION OF PENNSYLVANIA.

APPARATUS FOR ELECTROPLATING PIPES.

1,079,428.

Specification of Letters Patent.

Patented Nov. 25, 1913.

Application filed May 9, 1913. Serial No. 766,468.

To all whom it may concern:

Be it known that I, DANIEL H. MURPHY, a citizen of the United States, residing at Pittsburgh, in the county of Allegheny and State of Pennsylvania, have invented certain new and useful Improvements in Apparatus for Electroplating Pipes, of which the following is a full, clear, concise, and exact description, reference being had to the accompanying drawings, forming a part of this specification.

My invention relates to an improved apparatus for electroplating rods or pipe, by which the rods or pipe being treated are moved positively in the plating solution so that all portions of the surface of the rods or pipe are presented uniformly for the electrolytic operation. By my invention the operation may either be intermittent or continuous; and while the apparatus is somewhat different for the continuous operation from what it is for the intermittent operation, the essential constructional features characterizing my invention are incorporated in both arrangements.

It will be understood that while I shall refer throughout the specification and claims to the plating of pipes by means of my apparatus, I wish to have it understood that the apparatus will handle solid rods equally well; and furthermore, that the rods and pipes may have any desired cross section, as long as they may be made to roll upon the supporting surfaces which I provide.

An essential feature of the apparatus of my invention is a support for the pipes upon which they may rest and be rolled so as to present the surface of the pipes uniformly to the plating operation, and in combination with such a supporting surface I provide an operating member having a yielding surface in engagement with the upper surfaces of the pipe, so that by movement of said member the pipes are positively rotated in the plating solution. I provide this operating member with an inflated hose or tube which serves as the yielding means engaging the pipes. This tube, which is retained in operative position by any suitable retaining means, serves to effectually grip

the pipes and positively rotate the same in the plating solution.

In the drawings illustrating my invention Figure 1 shows, in cross section, a plating tank in which the parts are arranged for intermittent plating of successive lots of pipes; Fig. 2 is a top view of a form of plating tank in which the operation is continuous; Fig. 3 is a transverse sectional view taken on line 3-3 of Fig. 2, and Fig. 4 is a fragmentary detail view taken on the line 4-4 of Fig. 3 and looking in the direction indicated by the arrows, this view illustrating the relation between the pneumatic tube or hose, the operating member and the pipes to be plated.

Similar reference numerals refer to similar parts throughout the several views.

As shown in Fig. 1, the tank 1 contains transverse supporting members 2, preferably of wood, upon which the conductors 3 are located. The conductors 3 form supports for the pipes 4, which supports are substantially horizontal. A plurality of anodes 5 are disposed in the bottom of the tank so as to give proper distribution of the metal to be deposited throughout the solution in the tank. The pipes 4 are engaged upon their upper surfaces by operating members 6, each of which has secured to its lower surface a tube or hose 7, preferably of rubber. This tube or hose is provided with a suitable nonreturn valve 7^a, through which air may be passed into the tube to inflate the same. The said tubes 7 yield when they engage the pipes and thus permit positive engagement with all of the pipes in the tank. The tubes 7 serve effectually to grip the pipes because of the fact that they yield readily when brought into contact with the same.

While Fig. 1 of course illustrates but one each of the anodes 5, supporting conductors and operating members, I wish it to be understood that if a plan view of the tank shown in Fig. 1 were submitted, a plurality of each of these parts would appear. I have not thought it necessary to show a plan view of these parts, as the present invention is particularly concerned with the provision of the resilient means interposed between the

operating member and the pipes. This feature of the device of my invention is clearly illustrated in Fig. 1. The members 6 have formed on their left-hand ends brackets 8 which are engaged on their outer ends by levers 9 pivoted to supporting brackets 10 at 11. The levers 9 are connected by rods 12 with the cranks secured to a shaft 14 supported in suitable bearings 15. The shaft 14 is provided with a suitable pulley, not shown, by means of which it is rotated in order to reciprocate the members 6 and thus oscillate the pipes 4 in the tank. The ends 10 of the operating members 6 opposite to the brackets 8 are engaged by the guides 6^a to keep the operating members in proper position upon the pipes. The conductors 3, which are preferably of copper, are connected together and with one brush 19 of a plating generator 20, the other brush 21 of which is connected by a wire 22 with all of the anodes 5 employed in the tank. Extra anodes, as shown at 5^a, are provided above the pipes over the conductors 3 to make more uniform the distribution of the plating operation, which otherwise might be somewhat less, adjacent to the contact surfaces between the pipes and the conductors 3. The tank 1 is filled to a sufficient depth with plating solution so as to cover the anodes 5^a and the pipes are oscillated a sufficient length of time to receive the desired thickness of coating which may be of any desired material, usually copper or zinc.

In the embodiment of my invention shown in Figs. 2 to 4, inclusive, the tank 23 is so conformed that the conductors 24 forming the supports for the pipes 25 are at their ends above the top of the tank 23 and at each end are best so as to form inclined runways down into the tank, with level portions of the conductors across the bottom of the tank, thus affording supports for the pipes as they are about to enter the tank, as shown at 26, for subsequently leading the pipes down into the tank and across the bottom thereof and for afterward running the pipes up out of the tank to the position indicated at 27, after the plating operation has been completed. The pipes 25 are engaged during their progress through the tank by flexible belts which may be of canvas or rubber provided with inflated tubes or hoses 28 as shown. The tubes 28 are slightly compressed when brought into engagement with the pipes, as clearly shown in Fig. 3, thus serving to engage the pipes to move them through the tank. The belts are supported by guide wheels 29, 30 and 31, and pass over driving pulleys 32 so that the belts will take a position substantially parallel with the conductor supports 24^a. Backing plates 33, 34 and 35 are provided in the tank for securely holding the belt in engagement with the pipes between the guide

wheels. Suitable means may be provided for adjusting the distance between the supports 24^a and the belts, so that different sizes of pipe may be engaged and moved through the tank thereby, such means not being here shown in detail. The driving pulleys 32, 32 are mounted upon the shafts 36 and 37 connected together at 38 by a universal joint, said shafts being driven by a pulley 39 from any suitable source of power, not shown. The belts and tubes 28 are disposed obliquely in the tank 23 and at an angle to each other, as indicated, so that different parts of the pipes are engaged thereby as they are moved through the tank, as a result of which no particular part of the pipe is protected unduly in the plating operation by engagement with the conductors 24 and the tubes 28. Furthermore, by the inclination of the belts and tubes 28 in opposite directions, the resultant side thrusts upon the pipes as they pass through the tank are balanced and thus the motion of the pipes through the tank is without displacement toward one side or the other of the tank. In this modification, the anodes are located at 40 in the bottom of the tank and in practice electrical connections are made with the anodes 40 and the conductors in a manner similar to that shown and described in connection with the structure illustrated in Fig. 1.

The tank 23 may be made of such a length that a single passage through it by the pipes 25 will give them a sufficient thickness of deposited metal, or if desired, the pipes may be run through the tank a number of times or successively through a series of similar tanks so as to use different plating conditions, as desired, at different points in the process. The speed of the belts and tubes 28 may be varied, as desired, to change the length of time which the plating operation continues in the tank 23 upon any given pipe 25.

It should, of course, be borne in mind that any suitable means may be employed for securing the inflated pipe-engaging tubes to the members carrying the same. While in the drawings I have shown an arrangement wherein the inflated tubes are secured to their supporting members by means of rivets or bolts embedded in the tubes, I do not wish to be limited to this embodiment of my invention, but claim broadly any equivalent means for securing the inflated tubes to their supporting members.

What I claim and desire to secure by Letters Patent of the United States is:—

1. In an apparatus for electroplating pipes, the combination of a tank for containing the plating solution, a conductor support in the tank for the pipes to be plated, an anode in the tank, and an operating member disposed above said conductor

- tor support provided with an inflated tube, which tube is held in contact with the pipes to positively rotate the same, and mechanism connected with the operating member 5 for moving it to rotate the pipes.
2. In an apparatus for electroplating pipes, the combination of a tank for containing the plating solution, a conductor support in the tank for the pipes to be 10 plated, an anode in the tank, and an operating member provided with a readily compressible tube of substantially circular cross-section, said tube being held in contact with the pipes to positively rotate the same, and mechanism connected with the operating member 15 for moving it to rotate the pipes.
3. In an apparatus for electroplating pipes, the combination of a tank for containing a plating solution, said tank comprising a substantially horizontal support 20 for the pipes to be plated, an operating member provided with a readily compressi-
- ble inflated tube of substantially circular cross-section, said tube being held in contact with the pipes to positively rotate the 25 same, and mechanism connected with the operating member for moving it to rotate the pipes.
4. In an apparatus for electroplating pipes, the combination of a tank for containing the plating solution, an operating member comprising an inflated tube for simultaneously and positively engaging the topmost surfaces of a plurality of pipes, a conductor support in the tank for the pipes 30 to be plated, an anode in the tank, and devices connected with the operating member 35 for moving it to rotate the pipes.

In witness whereof, I hereunto subscribe my name this first day of May, A. D. 1913. 40

DANIEL H. MURPHY.
